UNITED STATES PATENT OFFICE

94,953

DESIGN FOR A BOTTLE OR SIMILAR CONTAINER

Seymour G. Epstein, Baltimore, Md., assignor to National Wholesale Liquor Company, Inc., Baltimore, Md., a corporation

Application December 15, 1934, Serial No. 54,433

Term of patent 3½ years

To all whom it may concern:

Be it known that I, Seymour G. Epstein, a citizen of the United States, residing at Baltimore, State of Maryland, have invented a new, original, and ornamental Design for a Bottle or Similar Container, of which the following is a specification, reference being had to the accompanying drawing, forming part thereof.

The figure is a front elevational view of a bottle or similar container, showing my new design.

The building block design effect may be continued entirely around the bottle.

I claim:

The ornamental design for a bottle or similar container, as shown and described.

SEYMOUR G. EPSTEIN.
